ABRADING MACHINE

Charles Johnson, Rockford, Ill., assignor to Mattison Machine Works, Rockford, Ill., a corporation of Illinois

Application August 15, 1930, Serial No. 475,569
Renewed February 15, 1934

28 Claims. (Cl. 51—135)

This invention relates generally to an abrading machine and more particularly to a machine for abrading and polishing or finishing materials in sheet form.

The preferred form of the invention as illustrated in the accompanying drawings and described hereinafter is particularly adapted for abrading and polishing extremely hard metal such for example as that generally known as stainless steel. This material is a chromium alloy and is so extremely hard that it has been difficult to finish or polish it in sheet form without a great deal of labor and expense. Generally it is desired to place a rather high polish on the metal so as to simulate nickel.

The difficulty of finishing such a metal may be readily appreciated from the fact that all ordinary forms of abrading machines have been found ineffective and heretofore special machines which have been constructed for this work have been cumbersome and expensive and have required a great deal of time in obtaining the desired finish.

The general object of this invention is to provide a new and improved abrading machine for finishing and polishing extremely hard material in sheet form.

Another object is to provide a new and improved abrading machine embodying an endless abrasive belt together with means for supporting a sheet of material and means for flexing the belt into engagement with the work sheet during relative movement between the flexed portion of the belt and the sheet, so that the entire sheet may be finished.

Another object is to provide an abrading machine for hard sheet materials embodying an endless abrasive belt, a support for the work sheet and means reciprocating along one run of the belt embodying means for flexing the belt into contact with the sheet around a curved surface having a relatively short radius.

Because of the extreme hardness of the metal it is necessary to apply considerable pressure to the abrading in order to obtain the desired action. This causes considerable heat which has a tendency to buckle the metal. It is therefore an object of the invention to provide a novel means for holding the work sheet flat on the work support to prevent buckling and to prevent movement of the sheet relatively to the support. In its exemplary form this means not only permits a reciprocating abrasive means to finish the sheet all the way to the ends thereof but also permits of transverse feeding of the work

support so that the abrasive means may finish the sheet all the way to its side edges. In this manner there is no wastage of material, the entire surface being finished.

Another object of the invention is to provide an abrading machine embodying a work support, reciprocatory abrasive means movable across said work support and a pair of roller means extending along opposite edges of the path of contact of said abrasive means on a work sheet and engaging the work sheet to hold it down on the work support while permitting transverse movement of the work support.

Further objects and advantages of the invention will become apparent as the description proceeds.

In the drawings:

Fig. 1 is a front elevational view of a preferred form of the invention.

Fig. 2 is an enlarged fragmentary view of the reciprocating abrasive means.

Fig. 3 is an enlarged fragmentary section substantially along the line 3—3 of Figs. 1 and 2.

Fig. 4 is a fragmentary front elevational view of another form of the invention embodying automatic means for reciprocating the work support transversely of the belt.

Fig. 5 is a transverse section approximately along the line 5—5 of Fig. 4.

Fig. 6 is a fragmentary plan view of the left hand end of Fig. 4.

While the invention is susceptible of embodiment in many different forms, I have shown in the drawings and shall herein describe in detail one such embodiment and a modified form thereof with the understanding that the present disclosure is to be considered as an exemplification of the principles of the invention and is not intended to limit the invention to the embodiment illustrated. The scope of the invention will be pointed out in the appended claims.

In the exemplary form illustrated in the drawings, the invention is disclosed as embodied in a machine of the general type shown in Patent No. 1,478,044 to C. L. Mattison dated December 18, 1923. Generally this machine has a base or frame comprising a pair of uprights or pedestals 5 connected by a lower cross member 6 and an upper cross member 7. Means including a pair of pulleys 8 and 9 rotatably mounted on the frame is provided for supporting and driving an endless abrasive belt 10. Preferably one of the pulleys such as 8 is driven by suitable means from an adjacent motor 11. The work W is arranged to be carried on a support

base mort
vletereqz
antrevsq

or table 12 which is positioned intermediate the uprights 5 and mounted for movement transversely of the belt by means of a plurality of rollers or wheels 13 operable on a pair of rails 14. These rails are carried on a pair of vertically adjustable slides 15. Preferably these slides may be raised and lowered simultaneously by means of vertical screws 16 (Fig. 4), which are rotatably mounted on the pedestals 5 and engage suitable nuts 17 on the slides, and are operable simultaneously by means including pairs of bevel gears 18 and a longitudinally extending shaft 19 which is formed at one end for receiving a suitable wrench or tool.

For applying the abrasive belt to the work supported on the table 12, the machine embodies a vertically movable horizontally extending guide bar 20 supported by means of a plurality of arms 21, rods 22 and 23 and brackets as more fully illustrated in said prior patent. On this guide bar is supported a longitudinally movable means 25 which is arranged to be reciprocated by means including a tape or band 26, secured at its opposite ends to the peripheries of a pair of pulleys 27, oscillating gear segments 28 which engage pinions 29 on the shafts of the pulleys 27, a rod 30 connecting said gear segments and a crank (not shown) having a pitman 31, for oscillating the gear segments. Since this mechanism is disclosed in detail in said prior patent the accompanying drawings illustrate only generally the construction of the parts.

Due to the hardness of the sheet material which is to be finished, it has been found that the reciprocating shoe structures such as are found in the prior art machines adapted for wood and other relatively soft materials, are wholly unsuited. The failure of these prior mechanisms was due principally to the fact that the means employed for applying the abradant to the work did not utilize the abrasive properties of the belt to the greatest extent, with the result that the belts would wear out quickly and without producing the desired finish on the work.

I have discovered that by flexing the belt around a curved surface of relatively short radius and into contact with the metal sheet so that only a relatively short portion of the belt is in contact with the sheet there is a tendency to project the abrasive particles on the belt into a more efficient contact with the metal and to separate adjacent abrasive particles so that independently they act upon the metal. Thus instead of the rubbing action obtained when the belt is applied by means of a flat presser member there is an efficient cutting action which results in a far quicker abrading of the sheet to the desired degree of finish or polish. Such rapid and efficient cutting action is of particular importance in the finishing of sheets of stainless steel since this material is extremely hard and the surface thereof must be abraded to a considerable depth to eliminate pits which are inherent in sheets of the material.

It has been found in practice that the flexing of a relatively short portion of the belt also serves to discharge foreign matter such as loose particles of the abraded material, loose or excessively worn particles of the abradant, and the loosened particles of adhesive. By reason of this positive discharging of the foreign matter caused by the positive and sharp flexing of

the belt, the formation of a non-abrasive glazed surface on the belt is prevented. In addition to this, this improved action of the belt on the metal generates less heat with the result that a suitable pressure may be applied without danger to the material.

In its preferred form as disclosed herein, the reciprocating means 25 comprises a frame member 35 having upper supporting rollers 36, lower rollers 37 and side rollers 38 rotatably mounted thereon for operation on the guide bar 20. A bracket 39 is secured to and extends downwardly from the frame member 35 and is bifurcated in form so as to provide longitudinally spaced portions 40 and 41 in which pulleys 42 and 43 are rotatably mounted. Intermediate the portions 40 and 41, a support 44 is mounted on a longitudinally extending pivot 45 and carries a pulley 46, the belt 10 passing over the pulleys 42 and 43 and under the pulley 46 as illustrated most clearly in Figs. 1 and 2.

The pivotal mounting for the support 44 for the pulley 46 permits this pulley to aline itself automatically with the upper surface of the work sheet on the table 12 as illustrated most clearly in Fig. 3. The pulley is rotatably mounted by means of ball bearings 50 on a shaft 51 and preferably the pulleys 42 and 43 are similarly mounted on shafts 52 and 53.

The pulleys carried on the reciprocating means serve as a means for flexing the adjacent run of the belt into contact with the work. The central pulley 46 is preferably laminated in form as shown in Fig. 3 and comprises a plurality of disks 54 of felt or other flexible material secured between metallic end members 55. This provides a pulley slightly yielding in character for effectively applying the belt to the work uniformly. The pulleys 42 and 43 serve as a means for maintaining the belt in contact with a substantial portion of the periphery of the laminated pulley 46 and are preferably provided with soft rubber rims 56 since they contact with the side of the belt carrying the abrasive material.

As mentioned hereinbefore, the finishing of extremely hard metal requires that the abrasive be applied with a considerable amount of pressure. This tends to cause local heating of the sheet and even buckling thereof unless efficient means is provided for preventing the buckling. The invention provides novel mechanism for preventing buckling. As illustrated herein, this means is in the form of roller means comprising a pair of rolls 60 and 61 extending longitudinally of the belt 10 and spaced laterally as shown in Fig. 3 so as to contact the work sheet along the edges of the path of movement of the pulley 46, or in other words along the longitudinal edges of the abrading zone. These rolls are rotatably mounted on a pair of brackets 62 secured to and extending forwardly from the pedestal portions 5 of the frame. In this way, the pressure of the rolls upon the work sheet may be adjusted by means of the screws 66 which are provided for raising and lowering the table 12.

Cooperating with the hold-down means for preventing buckling of the sheet, the invention preferably provides the table 12 with a plurality of heat radiating webs or fins 63 extending longitudinally thereof as shown best in Figs. 1, 3 and 5. The table is preferably of cast iron and the hold-down rolls and these fins separately or cooperatively serve as a means for preventing

buckling of the sheet, the rolls maintaining the sheet in contact with the table along the abrading zone and the fins effectively dissipating the heat generated.

- 5 This hold-down means serves not only to hold down the sheet of metal along the zone in which the abradant is applied so as to prevent any buckling, but also serves to clamp the sheet to the table and prevent movement of the sheet 10 relatively to the table. In this latter capacity it will be apparent that the hold-down roller means are particularly efficient in that they contact the sheet along the sides of the path of the pulley 46 and therefore permit the reciprocating abrasive means to contact the work all the way to the ends of the sheet. Furthermore the roller means permit transverse movement of the table and during such movement maintain a zone of constant width 20 upon which the abrasive means operates and also maintains a constant pressure on the sheet for clamping it to the table. The hold-down means therefore permits the table to be moved transversely so that the abrasive means may 25 finish the entire surface of the sheet all the way to the side edges, a single roll serving to hold the sheet down while the extreme edges are being finished. In this way there is no waste of material, since the entire surface is finished. 30 This is obviously true whether the sheet be rectangular in form or of any other shape.

The invention preferably provides automatic or power driven means for reciprocating the work support 12, such means being herein disclosed in Figs. 4 to 6. In this form of the invention the pedestals 5 are provided with forwardly extending brackets 62 attached to the adjacent faces of the pedestals for supporting the hold-down rolls. The table or work support structure in this form of the invention comprises a cast iron table or work support 12 mounted on a plurality of longitudinally extending I beams 70 which in turn are secured to transversely extending end members 71 and 72 45 and a central I beam 73. The end members 72 carry a plurality of wheels 13 operable upon rails 14 which are supported on vertically adjustable slides 15. Preferably the forward ends of the rails 14 are supported by means of adjustable pedestals 74.

The mechanism for reciprocating the work support is herein disclosed as comprising a rotatable drum 75 mounted on a shaft 76 on a frame 77 positioned beneath the work support. 55 A cable 78 is wound around the drum a plurality of times and has its opposite ends secured to a pair of brackets 79 and 80 as indicated most clearly in Fig. 5, said brackets extending downwardly from and being carried by the central 60 transverse I beam 73. Thus by rotating the drum in reverse directions, the table will be reciprocated due to the winding and unwinding of the cable on and from the drum.

The means for actuating the drum 75 is herein shown as comprising a worm wheel 81 on the shaft 76, a worm 82 engaging the worm wheel, a transversely extending shaft 83 for the worm, a cone pulley 84 on the front end of the worm shaft 83, an electric motor 85 having a complementary cone pulley 86, and a belt 87. The electric motor is arranged to be controlled by means including a drum type switch 88 which is supported on the left hand slide 15 (Fig. 4) with its operating arm 89 positioned adjacent 75 the left hand edge of the work supporting struc-

ture. This drum switch may be of any preferred construction having an operating arm with two operative positions, one as shown in Fig. 6 in which position of the switch the motor 85 would be operated to actuate the work support downwardly in said figure, and a second lower position wherein the motor 85 would be operated to move the work support upwardly in said figure. When the work support reaches the forward end of its travel, a dog 90 is arranged to engage the drum switch arm 89 and shift said arm to reverse the motor 85. Similarly at the rearward end of the work support movement, a dog 91 is arranged to engage the drum switch arm 89 to again reverse the motor. The dogs 90 and 91 are preferably mounted adjustably upon the left hand end member 71 (Fig. 4) so as to permit of varying the stroke of the work support transversely of the belt.

In its preferred form the invention also provides means for collecting the dust resulting from the abrading action. As illustrated herein the left hand portion 40 (Figs. 2 and 3) of the reciprocating means 25 is hollow and has a plate 92 across its lower end so as to substantially enclose the pulley 42. A slot 93 is provided across the portion 40 adjacent the right hand end of the said plate (Fig. 2) so that with the pulley 46 operating in a clockwise direction, the dust will be thrown into the portion 40 through said slot. This collecting of the dust is facilitated by providing a discharge opening 94 for the enclosure and connecting said opening to a suitable suction system. It will be noted that since the belt 10 rises sharply from the pulley 46 along the portion 40 the intake slot 93 may be positioned close to the point of contact of the belt with the work W.

In operation a work sheet is positioned on the table 12 and the table then raised until the hold-down means 60 and 61 contact the work with the desired pressure. Then the reciprocating means for the abrasive belt may be lowered so that the belt contacts the upper surface of the work with the desired pressure. During reciprocation of the abrasive means the table 12 may be moved transversely so that the entire work sheet will be finished. By varying the coarseness of the abrasive means on the traveling belt the desired finish can be obtained.

I claim as my invention:

1. A machine having, in combination, a frame comprising a pair of laterally spaced pedestals, an abrasive belt, means including rotatably mounted pulleys for supporting and driving said belt, slides movable vertically on said pedestals, means for adjusting said slides, transversely extending rails carried on said slides, a work table movable on said rails transversely of the frame, means for applying the belt to a work piece on said table comprising means reciprocating longitudinally on said frame embodying means to flex the belt into engagement with the work, and means for moving the table transversely, and means to prevent buckling of the work sheet comprising means for holding down the work sheet embodying brackets extending forwardly from said pedestals and a pair of rolls rotatably mounted in laterally spaced parallel relation on said brackets so as to engage the work sheet along the sides of the belt and means beneath the table for dissipating heat generated by the abrading action.

2. A machine having, in combination, a frame, an abrasive belt, means including rotatably

mounted pulleys for supporting and driving said belt, a work table movable transversely of the frame, means to apply the belt to a work piece on said table comprising means reciprocating longitudinally on said frame embodying means to flex the belt into engagement with the work and means for moving the table transversely, and means to prevent buckling of the work sheet comprising means for holding down the work sheet embodying a pair of roller means mounted in laterally spaced parallel relation on said frame so as to engage the work sheet along the sides of the belt and means beneath the table for dissipating heat generated by the abrading action.

3. A machine having, in combination, a frame, an abrasive belt, means including rotatably mounted pulleys for supporting and driving said belt, slides movable vertically on said frame, means to adjust said slides, transversely extending rails carried on said slides, a work table on said rails transversely of the frame, means to apply the belt to a work piece on said table comprising means reciprocating longitudinally on said frame embodying means to flex the belt into engagement with the work and means for moving the table transversely, and means to hold down the work sheet comprising brackets extending forwardly from said pedestals and a pair of roller means mounted in laterally spaced parallel relation on said brackets so as to engage the work sheet along the sides of the belt.

4. A machine having, in combination, a frame, an abrasive belt, means including pulleys for supporting and driving said belt, a work table slidably on said frame transversely of said belt, means to apply said belt to a work piece on said table including longitudinally reciprocatory means for flexing the belt into contact with the work, means for moving the table transversely, and means for holding the work down on the table including a pair of rolls rotatably mounted on said frame and engaging the work along the sides of the path of contact of the belt with the work.

5. A machine having, in combination, a frame, an abrasive belt, means including pulleys for supporting and driving said belt, a work table slidably transversely of said frame, means to apply said belt to a work piece on said table including reciprocatory means for flexing the belt into contact with the work, means for holding the work down on the table including a pair of rolls rotatably mounted on said frame and engaging the work along the sides of the path of contact of the belt with the work and means for preventing buckling of the work sheet including said hold down means.

6. A machine comprising, in combination, a frame, an abrasive belt, a work table slidably transversely of said frame, means to apply said belt to a work piece on said table including reciprocatory means for flexing the belt into contact with the work, and means for holding the work down on the table including a pair of rolls rotatably mounted on said frame and engaging the work along the sides of the path of contact of the belt with the work.

7. A machine having, in combination, an abrasive belt, means including pulleys for supporting and driving said belt, reciprocatory means for flexing the belt into contact with the work comprising a reciprocating carrier, a pair of laterally spaced rollers mounted on said carrier and over which one run of the belt passes,

and an intermediate roller mounted on said carrier and under which the belt passes into contact with the work.

8. A machine of the character described having, in combination, a frame, an abrasive belt, means for supporting and driving the belt, a work table movable transversely of the belt, and means for holding a work sheet down on said table comprising a pair of rotatably mounted rolls positioned in laterally spaced parallel relation and contacting the work sheet along opposite edges of said belt.

9. A machine of the character described having, in combination, a frame, a work table movable transversely on the frame, abrasive means on said frame arranged to move longitudinally of the table in engagement with the work, means for moving said table transversely and means for holding down the work on the table comprising a pair of laterally spaced longitudinally extending roller means mounted on said frame and engaging the work along the sides of the path of said abrasive means.

10. A machine tool having, in combination, a frame, a work table slidable transversely on said frame, a pair of laterally spaced longitudinally extending rolls rotatably mounted on said frame arranged to engage and hold down a work sheet on said table and permitting transverse movement of the table, said rolls defining a narrow strip of the work sheet therebetween on which an abrasive means may be applied, longitudinally reciprocating means for applying an abrasive means to the sheet intermediate the rolls, and means for reciprocating said table transversely during longitudinal reciprocation of said abrasive means.

11. A machine having, in combination, a frame, a transversely movable work table and means for holding down a sheet of material on said work table comprising a pair of laterally spaced longitudinally extending rolls rotatably mounted on said frame arranged to engage said sheet and hold down the sheet and prevent longitudinal movement thereof without obstructing the end portions of the sheet, and means moving longitudinally on said frame intermediate said rolls arranged to operate on said sheet, said table being movable transversely during said longitudinal movement to permit said operating means to contact the entire adjacent surface of the sheet.

12. A machine tool having, in combination, a frame comprising a pair of laterally spaced vertically positioned pedestals, slides movable vertically on adjacent faces on said pedestals, means for adjusting said slides, a pair of transversely extending rails carried one on each of said slides, a work table slidably mounted on said rails, a pair of brackets, one extending forwardly from each of said pedestals, a pair of rolls rotatably mounted between said brackets in laterally spaced parallel relation and arranged to hold down a work sheet positioned on said table and means movable longitudinally of said table intermediate said rolls for operating on the work sheet.

13. A machine tool having, in combination, a frame comprising a pair of laterally spaced vertically positioned pedestals, slides movable vertically on adjacent faces on said pedestals, means for adjusting said slides, a pair of transversely extending rails carried one on each of said slides, a work table slidably mounted on said rails, a pair of brackets one extending for-

wardly from each of said pedestals, a pair of rollers rotatably mounted between said brackets in laterally spaced parallel relation and arranged to hold down a work sheet positioned 5 on said table, an endless abrasive belt, means including pulleys for mounting and driving said belt with one run thereof passing above said table between said rolls and means mounted on the frame and slideable longitudinally thereof 10 arranged to apply said belt to the work sheet intermediate the rolls.

14. A machine of the character described having, in combination, a pair of laterally spaced hold-down roller devices mounted on stationary 15 axes, a work support adjustable toward and from a plane passing through said axes, an operating mechanism adjustable toward and from said devices and work support and also reciprocatory parallel to and between said hold- 20 down devices.

15. An abrading machine having, in combination, an abrasive belt, means including pulleys for mounting and driving said belt and a reciprocatory structure for flexing said belt into contact with the work comprising a pair of laterally spaced rotatably mounted guide pulleys over 25 which one run of the belt passes, a transversely swingable support positioned intermediate said guide pulleys and a pulley rotatably mounted 30 on said support engaging the belt and flexing it beyond said guide pulleys, said last mentioned pulley being laminated in form and comprising a plurality of disks of flexible material, and a housing substantially enclosing the guide 35 pulley over which the belt passes from said intermediate pulley and having an opening through which the dust resulting from the abrasive action may pass, said opening being positioned closely adjacent the point of contact of the belt with 40 the work.

16. An abrading machine having, in combination, an abrasive belt, means including pulleys for mounting and driving said belt and a reciprocatory structure for flexing said belt into contact with the work comprising a pair of laterally spaced rotatably mounted guide pulleys over 45 which one run of the belt passes, a pulley rotatably mounted intermediate said guide pulleys and engaging the belt and flexing it beyond said 50 guide pulleys, and means substantially enclosing the guide pulley over which the belt passes from said intermediate pulley and having an open-

ing through which the dust resulting from the abrasive action may pass, said opening being positioned closely adjacent the point of contact of the belt with the work.

17. An abrading machine having, in combination, an abrasive belt, means including pulleys for mounting and driving said belt and a reciprocatory structure for flexing said belt into contact with the work comprising a pair of laterally spaced rotatably mounted guide pulleys over 10 which one run of the belt passes, and a pulley rotatably mounted intermediate said guide pulleys and engaging the belt and flexing it beyond said guide pulleys.

18. An abrading machine having, in combination, a driven abrasive belt, and a reciprocatory structure movable across the face of a piece of work for flexing said belt into contact with the work including triangularly arranged guide elements spaced relatively closely together and 15 only one of which is adjacent to the work, said belt being passed over the side of said adjacent element next to the work and over the sides of the other elements remote from the work whereby said adjacent element bends the belt sharply 20 25 for contact with the work.

19. A machine of the character described comprising, in combination, an endless work performing belt, reciprocatory means having a path of movement along and adjacent to a piece of 30 work, means for driving said belt, a plurality of rotatable members engaging and operatively supporting said belt including a pair of spaced members mounted on said reciprocatory means and over which said belt passes, and an intermediate member under which the belt passes and 35 by which the belt is flexed into contact with the work.

20. In a machine of the character described, the combination of a work support having a 40 work engaging face adapted to support a sizable piece of work, a pair of hold-down rollers extending across said face in spaced substantially parallel relation, a driven endless abrasive belt having an active run extending generally across 45 said face between and substantially paralleling said hold-down rollers, and a reciprocating carriage mounted for movement longitudinally of said active run of said belt and including means for pressing said belt against the work between 50 said hold-down rollers.

CHARLES JOHNSON.
